UNITED STATES PATENT OFFICE.

JOSEPH JOUET, OF NEW ORLEANS, LOUISIANA.

SHUTTER-FASTENER.

SPECIFICATION forming part of Letters Patent No. 425,884, dated April 15, 1890.

Application filed June 25, 1889. Serial No. 315,459. (No model.)

To all whom it may concern:

Be it known that I, JOSEPH JOUET, a citizen of the United States, residing at New Orleans, in the parish of Orleans and State of Louisiana, have invented certain new and useful Improvements in an Iron Shutter Opener; and I do declare the following to be a full, clear, and exact description of the invention, such as will enable others skilled in the art to 10 which it appertains to make and use the same.

My invention relates to an improvement in devices for opening iron shutters, in which a lever with a metal rod or wire attached is made to operate in conjunction with iron 15 shutters; and the objects of my invention are to enable iron shutters of one or more windows on each floor to be summarily opened in case of a fire for inspection or introduction of a hose. I attain these objects by the mechanism illustrated in the accompanying drawings, in which—

Figure 1 is a front view showing attachment on a building. Fig. 2 is a front view showing attachment on a window-frame. Fig. 25 3 is a sectional view.

Similar letters refer to similar parts throughout the several views.

In constructing my invention I use a lever, as shown by F, which has a fulcrum or hinge, 30 as designated by H, the latter being held in position by securely fastening to the interior frame of window. Attached to lever F is a rod or wire E, to which is adjusted a bolt, B being a metal cross-bar with an opening D.

35 I is a staple on the shutter A.

C are springs.

G are wires.

In operating my device the shutters are closed as in the usual manner. The staple I 40 when the shutters are closed enters opening D in the cross-bar B, the shutters being thus fastened and resting against springs C. In case of a fire in a building which has my invention attached, the firemen are enabled at 45 a glance to see on what floor the fire is burning. One of the doors on the ground floor being suitably marked with a red ball or other design indicates that by opening that particular door the wires which connect with a lever on 50 one pair of iron shutters on each floor can be reached and one window on the floor in which

the fire is burning can be readily opened, a thorough inspection had, and the hose introduced with water for subduing the flames.

A striking advantage of my device is that 55 only one pair of iron shutters on each floor are opened, thus cutting off all draft and preventing the fire from spreading.

I am aware that it has been proposed by means of pulleys and wires to open all the 60 iron shutters on each floor of a building; but it has been found to be impracticable, as the wires lose their tension when strung around a pulley and cannot be used in as effective a manner as where attached to a lever, as done 65 by me, with a spring for throwing open the shutter when once the bolt in cross-bar B is released.

It will be observed that I have a device which may be applied to any ordinary window at present in use.

By providing the lever F with an angular portion a at one end I am enabled to bring the same in to the sash from the rear portion thereof and in a position to move the rod E with 75 its pin D in a true vertical plane and avoid employing anything but a common pivot-bolt to attach the lever to the window-sash. It will also be observed that I employ small springs C, and arrange them close to the hinge-edge of the blinds, so that they will be hidden 80 from view when the said blinds have been closed.

I am aware of the patent granted to Donahoe and Finn, January 2, 1883, in which shutters are fastened by a pin and pivoted levers carrying the fastening-pin are provided with pull cords or chains, whereby the said pins may be withdrawn, springs being also employed for throwing open the shutters after 90 the locking-pin has been withdrawn, and I therefore do not claim such devices nor combination of devices, broadly; but,

Having fully described my invention, what I claim, and desire to secure by Letters Patent, is—

The single lever F, pivoted about midway of its length to the upper cross-bar of a window-frame and having its inner end provided with the angular portion a, which passes 100 through the said frame, in combination with the window-frame having the cross-bar B, car-

rying a staple on its outer side, the hinged blinds, the springs C, secured to said blinds on the inner side thereof at the hinged edge, so as to be concealed from view when the 5 blinds have been closed, the staple I on one of the blinds, the pull-wire G, depending from the outer end of the angular lever F, and the wire E, carrying a pin and secured to the

angular end of said lever, substantially as specified.

In testimony whereof I affix my signature in presence of two witnesses.

JOSEPH JOUET.
